UNITED STATES PATENT OFFICE.

PERCY M. MOAK, OF MINNEAPOLIS, MINNESOTA.

VENDING DEVICE.

Application filed April 19, 1926. Serial No. 102,982.

The object of my invention is to provide a simple inexpensive device by means of which articles such as cigarettes in bulk can be dispensed or vended one at a time.

5 A further and particular object is to provide a vending device composed of but few parts and hence inexpensive to manufacture and not likely to get out of order or to require adjustment and repairs.

10 The invention consists generally in various constructions and combinations all as hereinafter described and particularly pointed out in the claims.

15 In the accompanying drawings forming part of this specification,

Figure 1 is a perspective view of a cigarette vending device embodying my invention;

20 Figure 2 is a vertical sectional view of the same showing the parts in their normal position;

Figure 3 is a similar view showing the plunger and slide in position to discharge a cigarette from the hopper;

25 Figure 4 is a sectional view on the line 4—4 of Figure 2;

Figure 5 is a sectional view on the line 5—5 of Figure 2.

In the drawing, 2 represents a suitable 30 casing having a cover 3 adapted for removal to place the cigarettes therein, and 4 is an inclined wall forming one side of the bottom of the cigarette containing chamber 5. 6 represents the side walls of this chamber 25 having offsets 7 at the lower ends forming guides 8 wherein a slide 9 is adapted to reciprocate and be operated back and forth in the guides by means of a finger grip 10 that is adapted to be operated by the person desiring a cigarette. An opening 11 is provided in the bottom of the casing over which the slide moves and cross members 12 and 13 are provided in said slide formed by bending the material of which it is composed, an opening 14 being provided between these cross members through which the cigarettes may drop one at a time upon the inclined shelf 15 having the upwardly turned lower end 16. The front wall of the 40 casing has a horizontal inwardly turned extension 17 over which the slide is adapted to operate, and above this shelf is a flat spring 18 substantially the full width of the casing and secured at 19 to the front wall thereof. This spring is made of a suitable 45 metal and has sufficient tension to normally

hold the slide in its withdrawn position as indicated by full lines in Figure 2, and when in this position the lower cigarette of the pile in the chamber 5 may drop down off the shelf 4 into the space between the transverse sections 12 and 13 and rest upon the edge of the shelf 17.

The forward wall of the transverse section 13 will be in substantial alignment with the lower edge of the plate 4 when the slide is in its normal position and will prevent the lower cigarette of the pile from tilting off the end of the shelf 17 into the opening 11. The spring plate 18 has its lower end bearing on the transverse section 12 and normally holds the slides in its retracted position as shown in Figure 2 and permits the lower cigarette in the chamber 5 to rest upon the end of the shelf 17. The lower end of the plate 18 is sufficiently below the plate 4 so that when the slide is pushed in by the pressure of the fingers on the grip 10, the plate 18 will be tensioned and its lower end engaging the lower cigarette of the pile will push it off the shelf 17 into the opening 11 and from thence the cigarette will drop by gravity upon the shelf 15 and slide down against the stop 16 in position to be grasped by the fingers of the user. The plate 18 has, therefore, two functions. By its tension, it normally holds the slide in a retracted position and returns the slide to this position when a cigarette or other article has been ejected. A further function of this spring plate is to push the cigarette or other article being vended, off the edge of the shelf 17 so that it will drop by gravity into the opening 11 when the slide is manipulated.

I thus am able to provide a dispensing device having a minimum number of parts. The coiled spring having no other function except that of a spring normally found in devices of this kind is entirely eliminated in my improved vending device. The flat spring plate 18 composed of suitable material has the double function of a spring and has an ejecting means for the cigarette and I, therefore, am able to produce an article of this kind that will be more simple in construction than devices of this kind as usually made and hence will not only be less expensive to manufacture in the first instance but will be less likely to get out of order and require repairs.

As soon as the slide has moved to the limit

of its inward movement and discharged the cigarette, the spring, upon the release of the slide by the operator will return it to its normal position moving the transverse section 13 to a point where it will prevent the bottom cigarette from tipping off the shelf 17 until the slide has again been moved inwardly to tension the flat spring and eject the lower cigarette from its resting place on the shelf.

I have shown and described the device used particularly for the vending of cigarettes, but it may be used for vending other articles of somewhat similar form or the construction of the support in the bottom of the chamber may be modified and other different shaped articles vended, utilizing the flat spring both as an aid in the vending operation and as a means for returning the slide manipulated by the user to its normal position.

The device may of course be made of any suitable material but I prefer to utilize sheet metal of suitable gauge on account of its comparatively light weight and the ease with which it may be formed or fashioned into the desired shape.

The device may be used in different positions and locations and is adapted particularly for attachment to the instrument board of an automobile so that the driver of the car can manipulate the plunger and slide with one hand and obtain a cigarette from the device without the necessity of removing both hands from the wheel. It will be understood also that I do not confine myself to the vending or dispensing of cigarettes alone as other articles similar in form may be placed within the vending chamber and dispensed one at a time in the manner described.

In various ways, the details of construction herein shown and described may be modified and still be within the scope of my invention.

I claim as my invention:

1. A vending device comprising a casing having a chamber therein and a support in the bottom of said chamber, a shelf below said support to receive the articles to be vended, said casing having a vending opening through which the articles in said chamber may be delivered one at a time, a reciprocating slide adjacent said opening and a spring plate adapted to normally hold said slide in its retracted position and serve as a means for discharging the article from said shelf when said slide is operated.

2. In a vending device, a reciprocating article-ejecting means and a support over which said ejecting means operates, said support being adapted to receive the lower article to be vended in the path of said eject-

ing means, and a spring device having the double function of normally holding said reciprocating means in its retracted position, and returning it to such position, and discharging the article to be vended from said support when said reciprocating means is operated.

3. A vending device comprising a casing having an inclined plate therein terminating at a point near the middle of said casing, a shelf provided beneath said plate and spaced therefrom for the discharge of the articles in said casing one at a time, an ejecting means operating above said shelf and a flat spring plate engaging said ejecting means and normally holding it in a retracted position and also engaging the article to be vended and discharging it from said shelf when said slide is operated.

4. A vending device having a chamber adapted to receive articles to be vended and provided with a discharge opening, and a support in the path of the articles falling through said opening, a slide operating above said support and comprising side members and transverse sections between them, said sections having an opening between them to register with the opening in the bottom of said casing, and means tending normally to hold said slide in its retracted position and permit an article to fall upon said support and be held thereon by one of said transverse sections, and said means being also adapted when said slide is operated to discharge the article to be vended from said support and also return said slide to its normal retracted position when released.

5. A vending device comprising a suitable casing adapted to contain cigarettes or like articles placed loosely one upon another therein, a support in the lower portion of said casing whereon the articles normally lie, an ejecting device adapted to engage articles upon said support, a spring member normally holding said ejecting device in its retracted position and adapted when said ejecting device is operated to discharge the articles one at a time.

6. A vending device comprising a casing having a chamber therein to receive the articles to be vended, an ejecting device and means cooperating therewith for supporting the lower article in the chamber in position to be dispensed, and means normally holding said ejecting device in a retracted position and adapted when said ejecting device is operated to discharge the lower article from the vending device.

7. A vending device having a chamber adapted to receive articles to be vended and provided with a floor in its lower portion and a vending opening, a shelf below said floor, an ejecting device having an opening therein through which the articles may

drop one at a time upon said shelf, and a spring device normally holding said ejecting device in its retracted position and adapted to engage the lower article of the pile resting upon said shelf and discharge it therefrom when said ejecting device is operated.

8. A vending device comprising a casing having a chamber therein and an inclined floor in the lower portion extending partially across said chamber and adapted to support articles placed loosely within said chamber, a spring plate forming a wall of said chamber and depending below said floor, the space between said plate and the

edge of said floor allowing the articles to feed through one at a time, a shelf below said opening whereon the lower article of the pile normally rests, an ejecting device operating between said shelf and floor and having an opening therethrough to register with the opening in the bottom of said chamber, said spring plate depending into the opening in said ejecting device in position to engage and discharge the lower article from said shelf when said ejecting device is operated.

In witness whereof, I have hereunto set my hand this 14th day of April, 1926.

PERCY M. MOAK.
